United States Patent Office

Des. 234,155
Patented Jan. 21, 1975

234,155

LAMP

Larry M. Gellert, Cincinnati, Ohio, assignor to
The First National Bank of Cincinnati

Continuation-in-part of abandoned application Ser. No.
156,574 June 24, 1971. This application Dec. 29, 1972,
Ser. No. 319,514

Term of patent 14 years

Int. Cl. D26—05

U.S. Cl. D48—20 R

FIG. 2

FIG. 1 is a perspective view of a lamp showing my new design.

FIG. 2 is a front elevational view of the lamp shown in FIG. 1.

This is a continuation-in-part of design application Ser. No. D. 156,574 filed June 24, 1971, and now abandoned.

I claim:

The ornamental design for a lamp, as shown and described.
